 International Business Machines Corporation,
 New York, N. Y., a corporation of New York

Application September 23, 1936, Serial No. 102,112

19 Claims. (Cl. 164—115)

This invention relates to a communication system, and more particularly to such a system for the transmission of statistical information and the like.

5 It is the principal object of the invention to provide a very simple and highly satisfactory communication system for the transmission of intelligence of the character of arbitrary indications arranged in predetermined coded positions 10 on a record card or the like.

It is a further object to provide a rapid and accurate communication system for use in conjunction with a tabulating card or the like having data recorded thereon and adapted to 15 produce the card with corresponding data at a remote point.

It is a further object to provide novel methods for the transmission and reproduction of any desired intelligence arranged as above described.

20 A further object is to provide a system adapted to the remote control of card punching apparatus, and a novel form of such apparatus particularly adapted to remote control.

A further object is to provide an apparatus 25 for selecting a desired group or plurality of groups of such arbitrary indications for transmission and reproduction.

A further object is to provide a novel form of tabulating card feed mechanism.

30 Other objects and advantages will be in part obvious and in part hereinafter pointed out in connection with the following description, the accompanying drawings, and the appended claims.

35 In the drawings:—

Fig. 1 shows a form of record card adapted for use in connection with the invention;

Fig. 2 shows a plan view of an automatic transmitter forming a part of the invention, and illustrating the scanning process;

Fig. 3 is a side view in part section on line 3—3 of the transmitter shown in Fig. 2;

Fig. 4 is a detailed view showing a preferred construction of the card feed belt of the invention;

Fig. 5 shows in somewhat schematic form the scanning arrangement comprising part of the transmitter of Figs. 2 and 3;

Fig. 6 is a plan view of the automatic perforator 50 showing the general arrangement of the card feed mechanism and the drive means therefor;

Fig. 7 is a side view of the perforator showing further details of the card feed mechanism, and the arrangement of the punching mechanism;

Fig. 8 shows the general arrangement of the

punch actuating magnets and their associated link work, on the line 8—8 of Fig. 7;

Fig. 9 is a detailed end view of the rotary contactor arrangement of Fig. 8 showing the relations of cam and contactor elements;

Fig. 10 shows, in schematic form, the actuating means for the positive clutch of the perforator power drive;

Fig. 11 shows, in schematic form, the electrical circuits of the transmitter;

Fig. 12 shows, in similar manner, the electrical circuits of the recorder; and

Fig. 13 shows in schematic manner the novel arrangement by which any desired part of the tabular data may be selected for transmission.

The present invention provides for the transmission of intelligence of any desired sort, but is arranged more particularly for the transmission of statistical data. For example, the invention provides a system for the transmission and reproduction of any of the types of information commonly contained on tabulating cards and the like. In such cards, the statistical information or data is arranged in the form of arbitrary indications coded according to their position on the card. The indications may be in the form of holes punched into the card, for example, or of marks of contrasting color or reflection characteristics with respect to the remainder of the card. For the purposes of this invention, cards of this nature will be referred to as record cards with indexed data.

A common form of tabulating card containing 80 columns may be used, and the card shown as an example in Fig. 1 is a form of record card adapted to the purposes of the invention, although it is to be understood that record cards may have any form suitable to the transaction or data to be transmitted. In the present instance, it is supposed that the record card (hereinafter termed the original) is one adapted to record data useful for production control, cost accounting, inventory accounting, and like processes related to mass production. The cards may be conveniently identified by serial numbers composed of numerals and signs, and may contain any desired coded information as to the article, material, process, operation or transaction to which they pertain, coded in the cards by any desired form of punching machine.

The coded information may be recorded in various divisions of the card termed fields, and arranged in vertical columns, and in horizontal levels or lines in well known manner. The vertical columns provide space for a punched hole

for each of the ten numerals, and two additional spaces in which a shift operation is recorded for the designation or printing of signs, etc., thus providing twelve indications in each column. A 5 card having 80 columns thus contains 960 coding areas. This of course is described as typical, as any desired number or arrangement of the fields etc. of the card may be provided.

The blank space at the head of each column 10 may be utilized for printing, and also provides an "underlap" interval in the scanning process in which a synchronizing signal is transmitted. By 15 "underlap" interval is meant that interval provided in the scanning process between the scanning of the different columnar fields of the card and during which a synchronizing signal is transmitted. The fields may be blank, or may be printed to indicate the interpretation of the coded 20 positions, thus permitting of visual verification.

20 Referring now to Figs. 2 and 3, a stack of record cards 1 is shown in position for automatic positioning and scanning, these steps forming part of the transmission process. The originals are 25 placed in the hopper 2 in a predetermined position, the correct registry of the cards being facilitated by the diagonally clipped upper left corner of the record card or other non-regular feature. A pair of spaced feed belts 3 driven by motor 5, with suitable transmission means therebetween, 30 remove the cards one at a time from the bottom of the stack, and advance each card to the scanning position. Feed belts 3 are preferably constructed of metal strips of predetermined length overlapped at the ends and joined to form a continuous belt. The outer edge of the overlap (see 35 Fig. 4) provides an edge of suitable thickness to engage only one card from the stack, thus insuring single draw-out of the cards. Each belt is provided with holes for engagement with the teeth 40 of the drive sprockets, and with guide projections 39 which guide the edges of the card.

Feed belts 3 are driven by feed sprockets 4 fixed to shaft 8, which in turn are intermittently driven by cam disk 7 operating on spur gear 6, likewise 45 fixed to shaft 8. Cam disk 7, which is firmly mounted on drive shaft 5' of drive motor 5, is provided with one transfer tooth by which it advances gear 6 one tooth pitch during a short arc 50 of its revolution. Gear 6 preferably has the same number of teeth as there are vertical column units in the card interval (say 90 column units). Hence drive motor 5 makes 90 revolutions for each revolution of feed sprocket 4 which in turn advances feed belt 3 one card interval, i. e., the 55 length of a card plus the space between cards. Drive shaft 5' also carries fixedly mounted thereon pinion 21 which in turn drives gear 26 fixed to counter shaft 25. Scanning sprocket 10, fixedly mounted on counter shaft 25, drives scanning 60 belt 11 provided with notches along each edge adapted to engage with a double row of teeth on scanning sprocket 10. Scanning belt 11 is stretched taut between scanning sprocket 10 and idler sprocket 10'. Scanning belt 11 is also provided with equally spaced scanning slits 11s, the slit spacing being slightly greater than the width of a record card, thus providing an "underlap" 65 interval in the scanning process.

The feed belts and scanning belt are so coordinated by the drive arrangement described 70 that in the "underlap" interval between cross-scannings of the record card, the record card is advanced along its length one column unit. The design of the gear trains, the diameters of the 75 sprockets, and other design factors are so chosen

that successive vertical columns of a record card are accurately positioned over the scanning slot 20s in table 20 each time a scanning slit 11s traverses the record card during the scanning process. It is to be noted that the feed and scanning systems are positively related, so that once being established, the proper registry conditions are maintained indefinitely.

Referring now to Figs. 3 and 5, a light source 14 is mounted in hood 13 over scanning belt 11 by 10 suitable mounting means not shown. A condenser prism 12 is positioned between light source 14 and scanning belt 11 in such relation as to focus the light upon the path of the scanning slits 11s, thus a narrow strip of light moves along scanning slot 15 20s as each scanning slit makes its traverse. Mounted below table 20 of the transmitter is a light responsive device 21, preferably a photo-electric tube or cell of elongated form, the length of the cathode thereof being sufficient to extend 20 beyond the ends of the scanning slot 22. Photo-cell 21 is housed in hood 23 to exclude extraneous light. The record cards are moved over the scanning slot 20s during the scanning process as previously described, and when a scanning slit 11s 25 comes into incidence with a punched hole, light from light source 14 is momentarily projected on the light reactive surface of photo-cell 21, causing a momentarily increased current flow therein in well understood manner. The light flashes 30 on photo-cell 21 generate electric signal impulses by means presently to be described.

Referring now to Figs. 6 and 7, there is shown the mechanism of the automatic card punching machine, termed the perforator or recorder. 35 Drive motor 30, of substantially uniform speed characteristics, and preferably of the same speed as motor 5 at the transmitter, drives drive shaft 30' upon which the phase corrector mechanism 35 is mounted. Sleeve 35', the driven member of 40 the phase corrector, is rotatable for correction purposes by the phase corrector in relation to drive shaft 30'. Clutch 39, of any desired type, but preferably positive in action, couples sleeve 35' to auxiliary shaft 35a under the control of 45 clutch magnet M2. (See Fig. 10). Auxiliary shaft 35a carries cam disk 47 and also cams 41 to 55 inclusive, of rotary contactor 48, one for each of the twelve punch units, and three associated with the synchronizing function, making 50 fifteen in all. The rotary contactor assembly 48 is equivalent to a rotary distributor of the type commonly used in printing telegraph apparatus, and such rotary distributors or other means having a similar function may be used in lieu of the 55 rotary contactor assembly shown. The cams 41, etc. have a single rise which closes paired contacts 41', etc. when in engagement therewith. The rises are staggered in a spiral configuration so that one revolution of auxiliary shaft 35a 60 closes each of the contact pairs in sequence. A slight "underlap" interval intervenes between the closing of each pair of contacts, thus providing a synchronizing and selecting margin.

The recorder is provided with a card hopper 62, 65 in which a supply of unpunched cards or blanks 61, preferably identical with the cards in which the original data was recorded, are stacked. A feed belt 63 is driven by sprocket 64, which in turn is driven intermittently by gear 66 and cam 70 disk 67, the latter being driven by auxiliary shaft 35a. The construction, size, arrangement and operation of the card feed mechanism at the recorder is preferably identical with that at the transmitter. Since the blanks correspond in 75

size and the columns are similarly arranged, the card feed requirements at the transmitter and recorder are the same. At the recorder a punching mechanism replaces the scanning mechanism at the transmitter, and by proper coordination of the two mechanisms, holes are punched in the blank cards in the same positions they occupy on the original card; hence an exact duplication of the original is obtained.

Referring to Fig. 7, the punching mechanism comprises a series of individually actuated punches 71, (in this case 12) properly spaced and guided by guide piece 72, and mating with suitable holes in die piece 73 mounted in table 70 of the recorder. The punches and holes may be of round section, or of rectangular section, depending on the type of tabulating equipment for which the cards are intended, being illustrated as rectangular in the present instance to conform with the holes in record card 1.

The series of punches 71 are preferably actuated individually by electromagnetic means, as for example means comprising a solenoid 81 operating through link work upon pivotally mounted toggle pair 74, 75. Link 74 has its lower end pivotally connected to punch 71 by means of a pin joint P1; link 75 has its upper end pivotally supported by fixed pivot P3 mounted on bracket 62b, and the two links are pivotally joined at knuckle joint P2. Clevis 76 is pivotally connected to P2 in common with links 74 and 75, and is in turn operatively connected to the solenoids by connecting rod 77. The toggle pair 74 and 75 is returned to unoperated position against stop 78 by retractile spring 79. The mechanism described is preferably uniform for all punches.

Because of the narrow spacing of the punch centers, the actuating solenoids 81 are preferably grouped in a systematic staggered arrangement such as indicated in Fig. 8. The solenoids are preferably arranged in three levels or banks. The plungers or armatures 82 of the middle level of solenoids are preferably connected directly to clevis 76 by connecting rod 77, which may be a separate part or integral therewith. The upper and lower banks are operatively connected to the toggle pair 74—75 by suitable link work, as for example, a system comprising lever 83, pivotally mounted at fulcrum P4, and pivotally connected to plunger 82 and connecting rod 77 by pin joints P5 and P6 respectively. The figure shows two magnets in each bank, the position of the remaining magnets being indicated.

The operation of the punching mechanism is as follows:—The solenoid 81, upon being energized, attracts its plunger 82, which reciprocates connecting rod 77 (either directly or by means of lever 83) straightening toggle pair 74, 75 which exert a downward thrust on punch 71 in well understood manner. After release of the magnetic pull, retractile spring 79 restores the toggle to position against stop 78. The card 61 is thus punched at a position depending upon which one of the punches is operated. The solenoids 81 are selectively energized in accordance with the printing signals sent from the transmitter by means of rotary contactor 40 as will be more fully described hereinafter.

Referring now to Figs. 3 and 11, the transmission of synchronizing and printing signals is accomplished in the following manner. The printing signal generating means has for its main elements light source 14, a light reactive device or photo-cell 21, scanning belt 11, a record card 1,

and an electronic relay T1 controlled by photo-cell 21. The synchronizing signal generating means has for its main elements cam 100 mounted on the drive shaft 5' (or otherwise coordinated in motion with scanning belt 11), contacts 101 operatively associated with cam 100, and electronic relay T1 controllable thereby. Cam 100 is so designed and arranged that it momentarily closes a control circuit for electronic relay T1 once for each cross-scanning of the card 1 in such relation to the movement of the scanning belt that the scanning belt is in the "underlap" portion of its cycle. Contacts 101 preferably are not closed during the entire "underlap" interval, but only during a portion thereof.

The signal transmission circuit has as its main elements power source or battery B, electronic relay T1, line transformer Tr1, and cut-off relay L1. Light reactive device 121 and shunting switch X are associated with the selection of columns or fields from which data is to be transmitted, which feature will be described hereinafter. Relay L2 and associated card switches X2 and X3 are associated with the control of the photo-cell 21 during intervals when a card is not in position over the scanning slot. Relay L3 and associated card switches X4 and X5 are associated with the control of the sending of synchronizing signals, both in connection with establishing synchronism of the recorder, and to provide automatic termination of the feed of blanks at the recorder when the last card of a batch of original cards has been run through the transmitter.

Light reactive devices 21 and 121 may be of any desired type. When used in connection with an electronic relay of the gaseous triode type, a gas photo-tube provided with a photo-emissive cathode and concentrated anode provides suitable characteristics. This type of photo-tube has a high dark resistance and good sensitivity, hence upon illumination, the percentage change in resistance is fairly high facilitating its application to the function of controlling electronic relay T1.

While electronic relay T1 may be of various types, the preferred form is a gaseous triode comprising a hot cathode, control grid and anode or plate all mounted in a sealed glass envelope containing an atmosphere of gas or vapor. Triodes of this type provide the advantages of ease of control, large current carrying capacity, quick ionization and deionization, and a high ratio of power controlled to control power. As is well understood, the grid of the typical gaseous triode can initiate ionization, but thereafter loses control and some means for reducing the anode voltage below the deionization potential must be employed to assist the grid in terminating the ionization current. Such means is represented by cut-off relay L1. In Fig. 11 capacitor C1 serves under normal conditions to hold the grid of T1 at cathode potential, while resistors R1 and R3 serve to limit the grid current to safe values upon ionization of T1.

Referring now to Fig. 12, the circuit arrangement of the recorder for utilizing the synchronizing and printing signals has as its main elements line transformer Tr2, electronic relay T2 (preferably similar in description to T1), rotary contactor 40 with its associated series of pairs of contacts, and a series of magnets M1, M2, M3, M4 to M15 inclusive energized selectively under control of rotary contactor 40. Magnets M1, M2, and M3 are associated with the synchronizing function, while magnets M4 to M15 inclusive are

the solenoids 81 described in connection with Figs. 7 and 8. The magnets named are each in branch plate-circuits of T2, the ionization current being interrupted at the rotary contactors 5 or by a cut-off relay similar to L1 of Fig. 11, if desired. Battery B2 holds the grid of T2 at a potential below the "trip" point. Cam switch X5 operated in accordance with the position of the feed belt 63 and card switch X6 located so that 10 it is operated by the card as it approaches the punch position and in a position generally corresponding to that of switch X1 at the transmitter, serve to cause registration of the first blank card in proper position to obtain placement 15 of the punched holes in the proper columns, and to provide for run-out of the final card on which recording has been accomplished. Resistor R2 is a grid-current suppressor resistor to limit the grid current of T2. The nature and function of 20 the various elements of the signalling and control circuits of the transmitter and duplicator will be more fully disclosed in connection with the description of the operation of these circuits.

Referring now to Figs. 3 and 11, transmission 25 of signals is effected as follows:—Assume that power is turned on the transmitter, and that the feed belt and scanning belt are in motion at the proper speed. In this condition, which may be termed the standby condition, electronic relay 30 T1 is supplied with operating potentials but remains non-ionized by reason of C1 holding the grid at a bias low enough to prevent ionization. Assuming now that a stack of original cards bearing tabular data is placed in the feed hopper, 35 feed belt 3 advances the bottom card until the card passes between the contacts of card switch X1 (see Fig. 11) whereupon the circuit through relay L3 is broken permitting contacts 103 to close as indicated. A circuit is thus partially 40 established from positive battery via contacts 103 and conductor 104 to contacts 101 and thence to the grid of T1. When contacts 101 are closed by the further rotation of cam 100 (mounted on shaft 5') positive potential is applied to the grid 45 of T1, ionizing same. A pulse of current through T1 and the plate circuit thereof, through the primary of line transformer T1, and the winding of cut-off relay L1, transmits a signal impulse to the line, the pulse being terminated by the opening 50 of the contacts of relay L1 whose action is timed to open the circuit at the proper time to produce a signal impulse of desired predetermined duration. The signal impulse initiated by the action of cam 100, repeated each time scanning 55 belt 11 reaches a predetermined phase position, constitutes the periodic synchronizing signals. Synchronizing signals are transmitted so long as the contacts of either card switch X1 or X4 are held open by the passage of a card. As shown, 60 switch X1 is located so that it is operated by the forward edge of the card before the card reaches the scanning slot, and switch X4 in series therewith is located beyond the scanning slot so that it remains operated until the trailing edge of the card has passed beyond the scanning position. Hence synchronizing signals are sent until after 65 the last card in the stack has travelled beyond the scanning slot 20s.

When a card approaches the scanning slot 20s, 70 it opens the contacts first of card switch X2 and then of X3 which are connected in parallel. The opening of the latter contacts breaks the circuit through the winding of relay L2, whose contacts 105 are released and close themselves, thereby 75 establishing a circuit from positive battery via

contacts 105 and conductor 106 through photo-cell 21 to the grid of T1. It should be noted that photo-cell 21 is not made operative until after a card has covered scanning slot 20s, and thereafter, when the scanning slot becomes uncovered by reason of running out of cards, or by reason of gaps between cards, photo-cell 21 is rendered inoperative. This precautionary feature avoids the possibility of false printing signals being transmitted by reason of light passing unobstructed from the light source to the photo-cell. When photo-cell 21 is made operative, as a scanning slit 11s moves into incidence with a hole in the record card, a beam of light passes from the light source to the photo-cell, illuminating the latter. As is well known, the effect of increased light striking a photo-cell is to decrease its resistance. Photo-cell 21 is connected in a circuit leading to positive battery, hence, upon the illumination of photo-cell 21, the potential of the grid of T1 is raised. Electronic-relay T1 is thus tripped, a current pulse is transmitted and terminated by cut-off relay L1 as in the previous case, hence the printing signals and synchronizing signals are of like duration and amplitude. It is to be noted, however, that while the synchronizing signals are periodic, the printing signals are aperiodic, their occurrence being determined by the position of the punched holes in the record card. 30

Referring now to Figs. 6, 7, and 12, the synchronizing and printing signals are utilized at the recorder in the following manner:—Assuming that power has been turned on at the recorder, and that a supply of blank cards has been placed in hopper 62, the contacts of card switch X6 and cam switch X5 will be considered as closed, completing a circuit from the positive side of battery B1 through the windings of magnet M2, and return via either or both of the switches named 35 to negative battery. Magnet M2 is thus energized, actuating pawl 112 (see Fig. 10) which releases clutch stop 39s causing the clutch jaws to engage and couple power to the card feed mechanism. The bottom card is thus fed from hopper 62 and is advanced by feed belt 63 until the card opens the contacts of card switch X6 as shown in Fig. 12. Cam switch X5 is so coordinated in motion with feed belt 63 that shortly before a card reaches card switch X6, the contacts of X5 50 open. Thus when the card opens the contacts of X6, the contacts of X5 being also open, clutch magnet M2 is deenergized, releasing pawl 112 which intercepts the stop pin on clutch 39, disengaging same and uncoupling the power drive. 55 This action effects the stopping of rotary contactor 40 in a predetermined registry position with switch 42' being closed as shown in Fig. 12. Simultaneously therewith cam switch 110 stops, and remains in the open circuit position shown. 60 Also the card is stopped at a predetermined distance from the center line of the punches 71. Card switch X1 at the transmitter is located to initiate the sending of synchronizing signals when an original card is at the same predetermined distance from the center line of scanning slot 20s. In this way, a blank card is stopped at the correct registry position so that upon resumption of feed motion in response to the first synchronizing signal from the transmitter, the first 70 blank card will be moved into position under punches 71 simultaneously with the positioning of an original card over scanning slot 20s. Initial corresponding alignment of the two cards having thus been secured, the alignment is thereafter 75

5 maintained automatically by the synchronizing and feed mechanisms. Thus under the control of the card the rotary distributor is brought into a predetermined position with respect to the synchronizing operation and the card itself also occupies a predetermined position with respect to the punch mechanism.

When the first synchronizing signal is received at the recorder, relay T2 is tripped, energizing 10 clutch magnet M2 and releasing clutch 39, thus applying power to the card feed, independently of switches X5 and X6. Following synchronizing signals hold clutch magnet M2 energized permitting the card feed to continue in unison with 15 that at the transmitter. As the blank card moves over the line of punches, printing signals from the transmitter arrive to trip T2, and the resulting current pulses therethrough are distributed to the punch actuating magnets M4—M15 in 20 proper timed order to select the punch operations corresponding with the punched holes of the original. In this way a duplicate card is prepared, reproducing exactly the holes punched in the original. After passing across the line of punches, 25 the duplicate is delivered to a receiving pocket not shown.

Should the rotary contactor depart from synchronism with the incoming synchronizing signals, the synchronizing pulse will be received 30 either at the time contacts 41' are closed or when contacts 43' are closed, depending upon whether the receiving machine is advanced or retarded in phase with reference to its proper position. If the pulse occurs when contacts 41' are closed, 35 corrector magnet M1 is energized which then applies a corrective action to the rotary contactor in the sense required to return it to proper synchronous position; corrector magnet M3 operates similarly in response to a departure from synchronism in the opposite direction and applies corrective action in the opposite sense. Any suitable means for applying the corrective action as controlled by the two corrector magnets may be used as desired. One form of such suitable means 40 for corrective purposes upon reception of the synchronizing impulses is shown in Patent No. 2,053,091, issued to W. S. Lemmon, in which the solenoids 35 and 56 are equivalent to applicant's magnets M1 and M3. In any case where a common source of synchronous power is available at 45 both transmitter and recorder, the corrective magnets M1 and M3 with their associated switch gear may be omitted. Magnet M2 will then control the driving operation of the rotary contactor in accordance with the periodic received signals.

Card switches X1 and X4 which control the sending of synchronizing signals from the transmitter, are so spaced that synchronizing signals are sent continuously so long as a card occupies 50 the scanning position at the transmitter. As the last card passes switch point X4, the synchronizing signals cease. However, the card at the recorder has already passed switch X6 so that this switch is closed and hence clutch magnet M2 remains energized through these contacts while the card feed continues to run out the last duplicate and bring a new blank into registry position ready 55 for the following run. As was described in connection with registry of the initial blank card, contacts X5 open just as or before a card reaches contacts X6; the card feed continues until a card opens contacts X6, causing the feed to stop, leaving switch X5 open, and bringing the next blank precisely to the registry point in preparation for 60 a subsequent operation.

In the foregoing description, it was assumed that data from all columns of the original would be transmitted. It is sometimes desirable, however, to transmit the data from certain columns only, and means are provided by the invention 5 for accomplishing such selective transmission.

Referring to Figs. 2 and 13, drive shaft 15 of card feed sprocket 4' carries mounted thereon a column selector wheel 113, which in cooperation with light source 114 and photo-cell 121 enables 10 the columns from which data is to be transmitted to be selected at will. Selector wheel 113 has its periphery divided into as many angular divisions as there are column units in the card feed interval (in this case 90). Eighty of these divisions, corresponding to the eighty columns of the record card, are numbered serially from one to eighty. These numbers are marked on housing piece 116, which also serves as a retainer member for segments or interceptors 117, one of which is provided for each of the eighty numbered divisions. The remaining divisions, representing the feed 15 "overlap" interval, are not used.

Each segment piece is movable for a limited distance in an axial direction, but by reason of the 20 fit of the parts and a light pressure exerted by housing 116, will remain in the position to which moved. Selector wheel 113 has a polished chamfered rim 113a, preferably cut at an angle of 45 degrees with respect to the axis of the wheel. The 25 arrangement of light source 114 and photo-cell 121 with respect to this rim are such that a beam of light from light source 114, being focused on rim 113a by condenser lens 115, will normally be reflected to photo-cell 121. Each segment 30 piece 117 is preferably provided with a small hole 117h properly placed so as to aid in adjustment of the position of the segment pieces. Access to these adjusting holes is afforded by slots in housing 116 as shown in Fig. 13. Photo-cell 121 is 35 housed in a suitable hood 122 to prevent extraneous light affecting its operation.

The operation of the selector arrangement is as follows:—By reference to an original card, the numbers of the columns which are not to be 40 transmitted are noted, and as the selector wheel is slowly rotated, the corresponding segment pieces are slid to their extended position by means of a small pointed instrument, the remaining segment pieces being moved within the housing. When in the extended position, the ends of 45 the segment pieces project into the path of the light beam, interrupting the light link between light source 114 and photo-cell 121. As shown in Fig. 13, the interceptors of columns 22, 23, 24 are 50 set to intercept the light link so no scanning in these columns will take place.

Referring now to Fig. 11, it will be seen that upon opening switch X, the final step in making the selector arrangement effective, photo-cell 121 55 is placed in series with photo-cell 21. Because of the high dark resistance of the photo-cells, when placed in series it is necessary to illuminate both photo-cells simultaneously in order to trip electronic relay T1. As a consequence, when the 60 columns corresponding to the extended segment pieces of selector wheel 113 are being scanned, photo-cell 121 will not be illuminated, and the scanning of those particular columns will be 65 ineffective to produce or transmit printing signals irrespective of punch marks therein. In order to obtain full transmission of the data, a cut-out switch X is provided which in practice is made 70 readily accessible to the operator for that purpose.

pose so that photo-cell 121 can be readily cut out of the circuit and its function eliminated.

It will be evident that the simple arrangement shown provides great flexibility and convenience 5 as regards the setting of the transmitter for selective transmission of data.

While the methods and forms of apparatus herein described constitute preferred embodiments of the invention, it is to be understood 10 that the invention is not limited to these precise methods and forms of apparatus, and that changes may be made therein without departing from the scope of the invention which is defined in the appended claims.

15 What is claimed is:

1. A communication system of the character described for use with a tabulating card containing a plurality of columns each having a plurality of positions for indications thereon, means 20 including light responsive means for scanning the positions of each column and successive columns, a single communication circuit, means for transmitting a signal in accordance with the position of each of said indications over said communication circuit, a recorder, means for receiving said signals, the recorder having a blank card corresponding to said tabulating card, means for moving said blank card intermittently through successive columns, and means controlled in response to said signals for reproducing 25 indications on said blank card corresponding to the respective positions of said indications on said tabulating card.

2. A communication system of the character 30 described which comprises a tabulating card having data arranged therein in the form of punches in predetermined coded positions, means including light responsive means for scanning said card, a single communication circuit, means for transmitting signals indicative of the position of each of said punches over said communication circuit, a recorder, a blank card at said recorder, and means operated in accordance with said signals for producing on said blank card punches corresponding in position to those on said recorder card.

3. A communication system of the character 35 described which comprises a tabulating card having indications arranged thereon in predetermined coded positions, a scanning device for scanning said card, means for transmitting signals indicative of the position of each of said indications, means for transmitting signals indicative of the position of said scanning device, a recorder, a blank card at said recorder, means controlled in accordance with said second mentioned signals for maintaining said recorder in synchronous operation with said scanning device, and means controlled in accordance with said 40 first mentioned signals for reproducing on said blank card indications corresponding to those of said tabulating card.

4. A communication system of the character 45 described for reproducing an original card having indications thereon comprising scanning means for said card, means for feeding said card into scanning position, means for transmitting signals indicative of the position of said indications and of the position of said original card, a recorder having a blank card, means at said recorder for reproducing indications on said blank card corresponding to those on said original card in accordance with received signals, means for feeding said blank card into predetermined position with respect to said reproducing 50

ing means, and means controlled in response to the feeding of said original card for initiating feed of said blank card.

5. A communication system of the character 5 described for reproducing an original card record comprising means for feeding said original card, means for transmitting periodic signals when said card reaches a predetermined position, a recorder having blank cards corresponding to said original card, means controlled in response to 10 said periodic signals for initiating feed of said blank card to establish corresponding position of said blank card with said original card.

6. A communication system of the character 15 described for reproducing an original record card comprising means for feeding said original record card, means for transmitting periodic signals when said card reaches a predetermined point, a recorder having a blank card, means for bringing a blank card into predetermined position in 20 said recorder corresponding to said predetermined point, and means controlled in response to said periodic signals for initiating the feeding of said blank card to establish movement of said blank card in corresponding relationship to said original card.

7. A communication system of the character 25 described for reproducing an original record card comprising scanning means for said card, means for advancing said card toward scanning position, means for transmitting a signal when said card reaches a predetermined point in advance of said scanning position, a recorder having a blank card, means at said recorder for reproducing the indications on said original card, means for moving said blank card toward reproducing position, and means controlled in response to said signal for initiating the feeding of said blank card from a 30 position corresponding to said predetermined point, to effect corresponding positioning of said blank card with respect to said original card.

8. A communication system of the character 35 described for reproducing a record card comprising scanning means for said card, means for feeding said card toward a scanning position with respect to said scanning means, means for transmitting a signal indicative of a predetermined position of said card in advance of said scanning position, and means rendering said scanning 40 means operative only when said card occupies 45 said scanning position.

9. A communication system of the character 50 described for reproducing the indications on a tabulating card or the like comprising means for scanning said tabulating card, means for moving said card toward and into scanning position with respect to said scanning means, means for sending periodic signals indicative of the position of said scanning means, means for initiating the sending of said periodic signals when said card reaches a predetermined position in advance of 55 scanning position.

10. A communication system of the character 60 described for reproducing the indications on a tabulating card or the like comprising means for scanning said tabulating card, means for moving said card toward and into scanning position with respect to said scanning means, means for sending periodic signals indicative of the position of said scanning means, means for initiating the sending of said periodic signals when said card reaches a predetermined position in advance of 65 scanning position, and means for continuing the transmission of said periodic signals until said 70

card passes to a predetermined position beyond said scanning position.

11. A communication system of the character described for reproducing the indications on a tabulating card or the like comprising means for scanning said tabulating card, means for moving said card toward and into scanning position with respect to said scanning means, means for sending periodic signals indicative of the position of said scanning means, means for initiating the sending of said periodic signals when said card reaches a predetermined position in advance of scanning position, a recorder having a blank card, means at said recorder for reproducing indications corresponding to those upon said original card, means for feeding said blank card into cooperative positioning with respect to said reproducing means, and means for initiating the feeding of said blank card in accordance with said periodic signals.

12. A communication system of the character described for reproducing the indications on a tabulating card or the like comprising means for scanning said tabulating card, means for moving said card toward and into scanning position with respect to said scanning means, means for sending periodic signals indicative of the position of said scanning means, means for initiating the sending of said periodic signals when said card reaches a predetermined position in advance of scanning position, a recorder having a blank card, means at said recorder for reproducing indications corresponding to those upon said original card, means for feeding said blank card into cooperative positioning with respect to said reproducing means, means for initiating the feeding of said blank card in accordance with said periodic signals, and means controlled in response to said periodic signals for regulating said feeding means to maintain said blank card in a position corresponding to that of said tabulating card.

13. A communication system of the character described for reproducing a tabulating card or the like having data arranged thereon in the form of indications, the card having a plurality of columns each containing a plurality of positions, comprising means for moving said card intermittently a distance corresponding to the spacing of said columns, means for scanning the positions of each column while the card is stationary in scanning position, means for transmitting timed signals corresponding to each movement of the card, and means controlled by said scanning means for transmitting signals intermediate said timed signals in accordance with the positions of said indications on the card.

14. In a communication system of the character described for reproducing a tabulating card or the like having data arranged thereon in the form of indications, the card having a plurality of columns each containing a plurality of positions, the combination of means for intermittently moving said card longitudinally a distance corresponding to the spacing of said columns to bring each column successively into a scanning position, and means traversing the card at right angles to the direction of movement thereof for scanning the positions of each column while the card is stationary in scanning position.

15. A communication system of the character described for reproducing a tabulating card or the like having data arranged thereon in the

form of indications, the card having a plurality of columns each containing a plurality of positions, comprising means for moving said card intermittently corresponding to the spacing of said columns, means for scanning the positions of each column while the card is stationary in scanning position, means for transmitting timed signals corresponding to each movement of the card, and means controlled by said scanning means for transmitting signals intermediate said timed signals in accordance with the positions of said indications on the card, a recorder having a blank card, means at said recorder for receiving said signals, means for feeding said card forward intermittently corresponding to the spacing of the columns on said tabulating card, means controlled in response to said timed signals for controlling said feeding means to cause feed of said blank card in accordance with movement of said tabulating card, and means actuated in response to said intermediate signals for controlling said recorder to reproduce on said blank card the indications on said tabulating card.

16. A remote controlled card punching mechanism of the character described having a blank card comprising means for receiving periodic synchronizing signals and aperiodic control signals, card punching means including a plurality of punches at different spaced points, feeding means controlled in response to said periodic signals for feeding said blank card into punching position with respect to said punching means, and means controlled in response to said aperiodic signals for effecting selective operation of said punches.

17. A communication system of the character described for reproducing a tabulating card or the like comprising a record card having a plurality of columns with data arranged in the form of predetermined indications in such columns, means for scanning said card, means controlled by said scanning means for transmitting signals in accordance with the position of said indications, and selectively operable means for causing the transmission of signals in response to indications in only predetermined ones of said columns.

18. A communication system of the character described for reproducing a tabulating card or the like comprising a record card having a plurality of columns with data arranged in the form of predetermined indications in such columns, means for scanning said card, means controlled by said scanning means for transmitting signals in accordance with the position of said indications, and means including light responsive means for rendering said scanning means responsive to only predetermined ones of said columns.

19. A communication system of the character described for reproducing a tabulating card or the like comprising a record card having a plurality of columns with data arranged in the form of predetermined indications in such columns, means for scanning the indications on said card, feeding means for feeding said card intermittently by a column width into scanning relation with said scanning means, and selective means movable with said feeding means for controlling the operation of the scanning means to render said scanning means non-responsive to selected columns of said plurality of columns.
